UNITED STATES PATENT OFFICE

GILBERT C. GREGG, OF STORM LAKE, IOWA

SAXOPHONE HIGH-NOTE KEYS

Application filed June 9, 1928. Serial No. 284,161.

This invention relates to an arrangement and means whereby the four high notes may be proficiently executed on a saxophone.

As is well known, even skilled saxophonists have difficulty in fingering the said four high notes. According to the present invention, such difficulty is removed and the keys controlling such notes are arranged so as to be operable by the left hand without being thrown out of position and thus in the natural way, the keys being arranged directly under the four fingers of the left hand.

Another object is to provide a construction wherein the D pad and the D sharp pad may be operated by a single key or selectively by individual keys as preferred.

Various additional objects and advantages will become apparent from a consideration of the description following taken in connection with accompanying drawings illustrating an operative embodiment, and wherein:

Figure 1 is a fragmentary view of a saxophone embodying my invention, the additional parts being omitted for the sake of clearness,

Figure 2 is a sectional view taken on the line 2—2 of Figure 1,

Figure 3 is a sectional view taken on the line 3—3 of Figure 1,

Figure 4 is a sectional view taken on the line 4—4 of Figure 1,

Figure 5 is a sectional view taken on the line 5—5 of Figure 1, and

Figure 6 is a sectional view taken on the line 6—6 of Figure 1.

Referring specifically to the drawings, 10 designates the usual tubular body of a saxophone having the usual D pad at D, the usual E pad at E, the usual F pad at F, and the usual D sharp pad at DX or E^b. Location of the aforesaid pads is as usual on the saxophone.

As is usual construction, pad E is connected by an arm 11 to a rod 12 which rocks on a longitudinal axis in bearings 13 and is adapted for operation at a key 14, for engagement as usual by the side of the right hand.

According to my invention, the pad E is adapted to be lifted through the depression

of a key 15 which is carried by a rod or lever 16 pivoted on a bracket 17 fastened to the body 10. Lever 16 has a link 17 pivoted thereto at 18 and pivoted at 19 to a crank 20 which is adjustably fastened by a screw 21 and sleeve 22 on the rod 12. The axes of the pivot members 18 and 19 are parallel to the rod 12 and its axis.

The F key has a rod or lever 23 extending therefrom which is also pivoted on the bracket 17. A key 24 is detachable to lift the pad F and is pivoted on a bracket 25 suitably fastened to the body 10 and has at its forward end a laterally extending lug 26 which underlaps lever 23.

The DX pad has a lever 27 extending therefrom which is pivoted on the bracket 25 and has an operating key 28 depressible in order to raise the pad DX. A lever 29 extends from the pad D, being pivoted to a bracket 30 suitably mounted on the body 10 and which is provided with a key 31 depressible to lift the pad D. It will be noted that the lever 29 is offset as at 32 and passes under the lever or arm 27. By reason of this construction, when the lever 27 is depressed it will also depress the lever 32. If preferred, however, the lever 32 may be individually operated from the key 31.

By reason of the arrangement shown, the keys 24, 15, 31 and 28 are arranged in a position for natural engagement by the first, second, third and little finger of the left hand in a natural manner. This compact and efficient arrangement enables the musician to execute the four high notes with maximum skill and ease.

It will be realized that although only the pads of the four high notes are shown, the saxophone is otherwise complete, the necessary parts being omitted in the drawings as forming no part of the present invention and the invention being more clearly illustrated and described because thereof.

Various changes may be resorted to provided they fall within the spirit and scope of the invention.

It will furthermore be understood that the arrangement of levers and keys herein-

before referred to is applicable to saxophones generally.

I claim as my invention:—

1. In a saxophone, an E pad, an F pad, a lever for actuating said E pad, a lever secured to the F pad, said levers being pivoted on the same axis, a D sharp pad, lever means to operate the D sharp pad, means pivotally mounting the latter lever, a lever pivotally mounted on the latter means underlapping the F pad lever, means to operate the F pad from the same axis as the lever means for the D sharp pad, a lever to operate the D pad, and keys for actuating the levers controlling the operation of said pads being arranged for convenient engagement by the fingers of the left hand.
2. In combination with the D, F, D sharp and E pads of a saxophone, levers controlling the lifting of said pads, means mounting the operating lever for the E pad and the lever secured to the F pad for operation from a common axis, a key for the lever of the E pad, a lever for operating the D sharp pad, means pivotally mounting the latter lever, a lever pivotally mounted on the latter means underlapping the F pad lever and provided with a key, a key on the lever of the D sharp pad, a lever extending from the D pad, means pivotally mounting the latter lever, the latter lever extending under the lever for the D sharp pad and being provided with a key, said keys being arranged for convenient engagement by the fingers of the left hand.

In testimony whereof I affix my signature.
GILBERT C. GREGG.
